DESIGN FOR A STAMP OR SIMILAR ARTICLE

Arthur Strauss, New York, N. Y.

Application July 2, 1940, Serial No. 93,384

Term of patent 3½ years

To all whom it may concern:

Be it known that I, Arthur Strauss, a citizen of the United States, residing in New York city, in the county of New York and in the State of New York, have invented a new, original, and ornamental Design for a Stamp or Similar Article, of which the following is a specification, reference being had to the accompanying drawing, forming part thereof.

The single figure is a plan view of a stamp showing my new design enlarged on a scale of 4 to 1.

I claim:

The ornamental design for a stamp or similar article, substantially as shown and described.

ARTHUR STRAUSS.
